UNITED STATES PATENT OFFICE.

JOHN MARLAND, OF WEST BRIDGEWATER, MASSACHUSETTS.

IMPROVED PROCESS OF MANUFACTURING DELAINES.

Specification forming part of Letters Patent No. 15,703, dated September 9, 1856.

To all whom it may concern:

Be it known that I, JOHN MARLAND, of West Bridgewater, in the county of Plymouth and State of Massachusetts, have invented a new and improved method of preparing and working wool for the manufacture of delaines and other similar fabrics, of which the following is a full, clear, and exact description.

Yarn spun from carded wool, owing to the knots and other impurities which still remain in it, and which are never entirely eradicated by the card, are destitute of that evenness of size and uniformity of texture necessary to render it fit for the manufacture of thin and highly-finished fabrics. On this account it becomes necessary to manufacture such goods of worsted yarn, which is spun from combed wool and possesses the desired evenness and uniformity. These fabrics, however, when manufactured entirely of worsted-yarn, owing to the straightness and parallelism of the fibers, have a harshness of feel and a stiff, rigid appearance, which it is extremely desirable to do away with.

To accomplish this end, and to unite the advantages of these two methods of working the wool without the disadvantages attendant upon either, is the object of my present invention, which consists in a union of the two processes of combing and carding, whereby the evils attendant upon the sole use of either are entirely avoided, and the soft feel and pliant texture of the one are united with the evenness of thread and uniformity of appearance of the other.

My process may be employed either for the purpose of extracting and utilizing a portion of the wool heretofore left in the noil after the longer fibers are taken out by combing; or it may be applied to shorter-stapled wool, nearly the whole of which may thereby be rendered available for the manufacture of soft and even yarn.

To enable others skilled in the art to understand my invention, I will proceed to describe the manner in which I have carried it out.

Where long-stapled wool is employed, the longest fibers are combed out for the production of worsted yarn, and a large portion of the shorter wool remains behind in the noil, and with it is devoted to the manufacture of fabrics of an inferior quality. To render available this

shorter-stapled wool, which has heretofore passed off with the noil, after the long staple is withdrawn, I subject the noil to a second draft, with rollers placed much nearer to the comb-teeth than those which withdraw the long fibers, by which means this shorter staple is drawn out and freed entirely from knots, the impurities and very short and tangled fibers only remaining behind as noil. The straightened and combed wool thus obtained by this second draft is now submitted to the second step of my process, which consists in carding it upon any ordinary carding-engine, and from the sliver thus produced an exceedingly fine and uniform yarn may be spun, which at the same time possesses the softness and pliancy of yarn manufactured of carded wool, and the evenness and uniformity of thread possessed by worsted-yarn. The same result follows where a short-staple wool is operated upon. In such case it is first combed upon any ordinary combing-machine, the drawing-rolls being placed, as before, so near to the comb-teeth as to withdraw all the fibers of a length which it is desirable to extract, the very short fibers and the impurities only remaining in the comb as noil. The fibers thus extracted are then, as before, passed through an ordinary carding-engine, and the yarn spun from the resulting sliver, as in the former case, is at the same time soft and even.

By the above-described process of treating wool a yarn is produced of a quality superior to any before manufactured, at the same time that a great economy of material is effected, as a lower grade of wool may be employed to produce the same size of yarn; or where very long-staple wool is used, the longest fibers may be extracted for the manufacture of worsted, and a large amount of the fiber heretofore allowed to remain in the noil utilized and employed in the finest fabrics.

What I claim as my invention, and desire to secure by Letters Patent, is—

The within-described method of operating upon wool by combing and subsequently carding, in the manner and for the purpose substantially as herein set forth.

JOHN MARLAND.
